LUTHER P. BROWN, OF RAMSEY, NEW JERSEY, ASSIGNOR, BY MESNE ASSIGNMENTS,
TO EMPIRE PAPER BOTTLE COMPANY, A CORPORATION OF NEW JERSEY.

FIBROUS CONTAINER.

1,243,698.

Specification of Letters Patent. Patented Oct. 23, 1917.

Application filed January 8, 1912, Serial No. 669,955. Renewed March 14, 1917. Serial No. 154,896.

To all whom it may concern:

Be it known that I, LUTHER P. BROWN, a citizen of the United States, residing in Ramsey, county of Bergen, and State of New Jersey, have invented a certain new and useful Fibrous Container, of which the following is a specification.

This invention is a fibrous container, and the object of the invention is to make a container of the type specified adapted especially for containing liquids, such as milk, having a tapering neck of substantially the same form as that of an ordinary milk bottle.

15 Heretofore it has been proposed to mold milk bottles from paper pulp, but so far as I am aware no one has, prior to my invention, constructed a bottle having a tapering neck from paper.

20 With the object specified in view, this invention embodies a paper receptacle or bottle for containing liquids, the neck of which is tapered by producing folds in the paper, lengthwise of the neck, at the desired points, resulting in a bottle the mouth of which is smaller than the body of the receptacle.

The folds referred to not only permit of the bottle being tapered, as specified, but 30 they perform several other important functions such as imparting strength to the neck and mouth of the bottle, providing for the expansion of the contents of the bottle, and assisting in the handling of the bottle by 35 providing a frictional surface which can be easily and firmly gripped by the hand. The said folds are formed by depressing the paper on the desired lines, *i. e.*, producing folds therein, the depth of which are considerably greater at or near the mouth of 40 the bottle than at the points where the folds start, thereby resulting in gradually tapering folds.

In the preferred construction, while the 45 neck of the bottle is tapered as specified, the mouth thereof is cylindrical, thereby providing a convenient shape for closing, as well as for filling and emptying, the bottle. The mouth of the bottle is preferably provided with internal and external cylindrical rings which securely retain the folds of the 50 bottle as well as adding strength to the bottle, the inner ring performing the further function of providing a smooth surface 55 for facilitating the pouring of the contents

of the bottle. The said rings are preferably secured to the mouth of the bottle by cement.

Another feature of the invention consists in providing the receptacle with a molded bottom member provided with a downwardly extending circumferential flange over which the side walls of the bottle are crimped and cemented, thereby securing a firm base for the bottle united thereto by a liquid tight joint.

In the accompanying drawings, I have illustrated one practical embodiment of the invention, but the construction shown therein is to be understood as illustrative, only, 70 and not as defining the limits of the invention.

Figure 1 is a vertical longitudinal section through a paper bottle constructed in accordance with this invention, the plane of 75 the section being indicated by the dotted line 1—1 of Fig. 2.

Fig. 2 is a plan view of the mouth portion of the bottle, a portion of the neck thereof being shown as broken away. 80

Fig. 3 is a horizontal transverse section on the line 3—3 of Fig. 1.

The bottle A is formed of fibrous material, the same being composed of paper and wound upon a mandrel so as to produce two 85 or more plies or layers, as at a in Fig. 1. The neck B of the bottle tapers from the cylindrical body A toward the cylindrical mouth C, said taper being imparted to the neck by forming therein a series of folds D. 90 The folds extend lengthwise of the bottle, they converge from the cylindrical part of the body to the mouth, and they extend to the outlet edge of the bottle. The folds D produce a series of ribs in the tapering neck 95 of the bottle, said ribs being shown as positioned on the inside of the neck, although it is evident that the folds or ribs may be exteriorly to the bottle. The ribs are each tapering in form so that the rib increases in 100 depth from the upper end thereof toward the lower end, such taper of the series of ribs taking up considerable of the paper material adjacent to the mouth and the decrease in the depth of the ribs toward the 105 body allowing more of the paper material to remain in the walls of the neck, whereby the desired longitudinal tapering form is given to the neck between the body A and mouth C.

At the mouth of the bottle the upper parts of folds D are compressed upon themselves and bent upon the walls of paper material so as to produce a substantially cylindrical mouth portion, the bent series of compressed folds being in lapping order as shown in Fig. 3. The increase in the thickness of the paper material due to the bending of the folds in lapping order produces a substantially rigid mouth at the outlet from the bottle, and the stiffness and strength of this mouth portion C is increased by the employment of one or more substantially cylindrical rings.

15 As shown, two rings E, F are employed, the ring E being positioned in the mouth and within the bent end portions of folds D, whereas ring F is externally to the bent ends of folds D. The rings E, F are united 20 in a suitable way to the compressed and bent end portions of the folds, preferably by cementing the rings in position and upon said ends of the folds, whereby the rings substantially incase the folded material at the mouth 25 portion of the bottle, for the purpose of retaining the folded material permanently in position, besides adding stiffness and strength to the mouth of the container. The inner ring E provides a smooth cylindrical 30 surface for the inflow or outflow of the material, usually liquids, thus precluding to a substantial extent the lodgment of the liquid material within the mouth of the bottle. Similarly, the external ring F presents a 35 smooth exterior surface, upon which may be fitted a flanged cap for closing the mouth of the bottle.

The ribs formed by the longitudinal folds at the neck of the bottle perform important 40 functions in addition to the primary one of so taking up the material as to produce the taper in the neck. Among these additional functions secured by the folds in the neck are, first, the ribs add materially to the rigidity, stiffness and strength of the neck portion; second, they permit expansion of the 45 contents of the bottle consequent upon a thawing out of the liquid should it become frozen within the bottle, as is frequently the case when milk is delivered to customers 50 during cold weather and is permitted to remain out of doors for several hours; and, third, the presence of the ribs impart a certain irregularity to the external surface of 55 the neck portion of the bottle, which roughened surface affords a means whereby a good grip may be obtained on the bottle when handling it.

In addition to the ribs formed by the 60 folds, the body A of the bottle is provided with an annular bead or groove G at the base of the tapering neck, or between the latter and the cylindrical body A, see Fig. 1. This annular groove imparts a certain 65 amount of stiffness to the body and it allows,

also, a limited expansion of the body should the liquid therein become frozen and then be thawed out.

H is the bottom of the bottle. It is composed, preferably, of paper molded or 70 pressed into the form shown, thus producing a solid and substantial closure which is united permanently to the bottle in a liquid 75 tight manner. The bottom is provided with an integral central depending member h and with an integral depending annular flange h', the latter being exteriorly to and around the central member, see Fig. 1. During the manufacture of the bottle, the bottom is positioned within the lower part 80 of the cylindrical body A, well above the bottom edge thereof, the flange h' of the bottom being in close contact with the annular wall of the body. The bottom and its flange are united to the body in a suitable 85 way, as by cementing the flange and bottom to the body, and thereafter the lower end edge portion of the material composing the body is folded, bent or crimped, as at i, around the peripheral flange h' of the bottom. Said folded part i of the body is united, by cement, to the flange of the bottom, whereby the flange is substantially 90 incased within the material composing the body A, thus resulting in a permanent attachment of the bottom to the body and in 95 the production of a liquid tight joint between these parts.

The paper bottle is rendered water or liquid proof by suitable materials incorporated in the paper or applied to the bottle 100 during or subsequent to its manufacture. Obviously, the paper may be saturated or coated with paraffin, or other water proofing agent, prior to making the bottle, or 105 after the bottle shall have been made, it may be saturated or coated with the water proofing agent. The water proofing agent, or other material used in treating the paper or the product resulting therefrom, operates 110 also to impart a certain degree of translucency to the bottle so that the level of the liquid therein may be determined by observation.

A paper bottle constructed as herein 115 shown and described is capable of manufacture by suitable machinery in large quantities so as to produce them rapidly and economically. The bottle is sufficiently rigid to successfully withstand a considerable amount 120 of rough handling without breaking or cracking the same so as to result in the loss of the liquid contents. In fact, the bottle is well adapted for general use, although it is intended to be used mainly for dispensing 125 such necessary materials for human consumption as milk, etc. It is produced so economically that when once used it can be thrown away like an ordinary carton in which crackers, etc., are packed.

Having thus fully described the invention, what I claim as new, and desire to secure by Letters Patent is:—

1. A paper bottle comprising a tubular body portion, an annular collar at the mouth portion, and a tapering neck portion intermediate the body portion and the mouth portion, said bottle being composed of a web or sheet of paper coiled upon itself to produce successive enveloping windings and the material of said neck portion being folded to produce longitudinal ribs positioned internally of the bottle and increasing in depth from the tubular body portion to the mouth portion, said folded material composing the ribs being deflected at the mouth portion into lapping relation to the unfolded material and producing a stiffened reinforced mouth collar the thickness of which exceeds the thickness of the material composing the tubular body. 5
2. A paper bottle comprising a tubular body portion, an annular collar at the mouth portion, and a tapering neck portion intermediate said body portion and the mouth portion, said bottle being composed of a web or sheet of fibrous material coiled upon itself to produce successive enveloping windings, the material of said tapering neck portion being folded upon itself to form a series of ribs positioned internally of the bottle and extending radially to the longitudinal axis thereof, said ribs increasing in depth from the tubular body portion to the annular mouth portion and the folded material composing said ribs being deflected at said mouth portion into lateral lapping relation to the infolded material at said mouth portion, said folded and lapping material producing with the infolded material a stiffened reinforced annular mouth collar the aggregate thickness of which exceeds the thickness of the material composing the tubular body. 10
3. A paper bottle comprising a tubular body, an annular mouth and a tapering neck, said bottle being composed of a web or sheet of paper wound successively upon itself and with the material composing the neck folded to produce longitudinal tapering ribs extending from the tubular body to the edge of the annular mouth, said folded material of the ribs being flattened at the annular mouth to produce plaits which overlap the unfolded material and which plaits are positioned substantially in contact with each other and are in substantially flush relation to each other, thereby resulting in a stiffened reinforced mouth collar the thickness of the aggregated folded and plaited material of which exceeds the thickness of the material composing the tubular body. 15
4. A paper bottle comprising a tubular body, an annular collar at the mouth portion, and a tapering neck extending intermediate said annular collar and the tubular body, said bottle being composed of a web or sheet of fibrous material coiled upon itself to form successive enveloping windings, the material composing the tapering neck being folded upon itself to produce a series of tapering ribs positioned internally of, and radially to the longitudinal axis of the bottle said material of the ribs forming on the exterior surface of the neck a series of open longitudinal channels which increase in depth from the tubular body to the annular mouth, the end portions of said folded ribs being compressed into lapping relation at the annular mouth and producing a stiffened reinforced collar the thickness of the aggregated folded and plaited material composing which collar exceeds the thickness of the material forming the tubular body. 20
5. A paper bottle comprising a tubular body, an annular mouth portion and a tapering neck connecting the tubular body and the annular mouth, said bottle being composed of a web or sheet of fibrous material wound upon itself and with the material comprising the tapering neck folded to produce a series of longitudinal tapering ribs, said ribs at the mouth portion being compressed into lapping relation to the unfolded material exteriorly thereof, an inside band contacting with the folded material of the annular mouth, and an external band contacting with said folded and lapping material of the mouth portion, said bands coöperating to confine the folded material and presenting smooth surfaces at the mouth portion of the bottle. 25

In testimony whereof I have signed my name to this specification in the presence of two subscribing witnesses.
